UNITED STATES PATENT OFFICE

127,049

DESIGN FOR A TEXTILE FABRIC

Arthur Eichler, New York, N. Y.

Application March 12, 1941, Serial No. 99,518

Term of patent 3½ years

To all whom it may concern:

Be it known that Arthur Eichler, a citizen of the United States and resident of New York city, in the county of Queens, State of New York, has invented a new, original, and ornamental Design for a Textile Fabric, of which the following is a specification, reference being had to the accompanying drawing, forming part thereof, and in which,

The figure is a plan view of a piece of textile fabric, showing my new design.

I claim:

The ornamental design for a textile fabric, substantially as shown.

ARTHUR EICHLER.
